UNITED STATES PATENT OFFICE.

JAMES SPEAR, OF PHILADELPHIA, PENNSYLVANIA.

HOUSE-FURNACE.

SPECIFICATION forming part of Letters Patent No. 325,281, dated September 1, 1885.

Application filed November 10, 1884. (No model.)

To all whom it may concern:

Be it known that I, JAMES SPEAR, a citizen of the United States, residing at Philadelphia, Pennsylvania, business address 1016 5 Market street, Philadelphia, have invented a new and useful Improvement in House-Furnaces, of which the following is a specification.

My invention relates to the construction of 10 the dust-flue and its connection with the ash-pit and combustion-chamber, and in providing a greater convenience for the removal of slate and clinkers from the grate-surface.

In the accompanying drawings, illustrating 15 my invention, Figure 1 is a vertical section through the furnace. Fig. 2 is a vertical section through the lower head or bottom plate of the combustion-chamber. Fig. 3 is a perspective view of the same with the dust-flue 20 collar in section. Fig. 4 is a vertical section through the top plate of ash-pit base. Fig. 5 is a perspective view of the same with dust-flue collar in section to show the damper.

I construct my furnace with a base-plate, 25 A, ash-pit sides a', ash-pit top plate, B, fire-pot C, grate F, fire-pot lining D, dust-flue E, combustion chamber or drum H, lower drum-head, h', top drum-head, h'', upper drum, N, containing air-tubes, smoke-collar K, sheet- 30 iron casing M, feed-door h', ash-pit door a'', clean-out doors P, for inserting a poker to remove the cinders through the anti-clinker opening S between the grate and fire-pot, dust-damper e', and cold air inlet collar R at 35 the rear of the casing.

I construct the top plate, B, of the ash-pit separate from the sides a', and form in it a

ring at b', as a seat or support for the fire-pot. The front of this plate B is turned or inclined upward at b'', that a person may operate upon 40 the slate and clinkers by means of a poker without stooping to the horizontal line of the said plate. In this inclined front plate is cast a collar, e'', forming a portion of the dust-flue E. The lower drum-head, h', is inclined like 45 a funnel toward the top of the fire-pot, so that the dust and ashes settling on it are easily removed into the fire-pot, and thence into the ash-pit through the grate. Upon this lower drum-head, h', is cast a collar, h'', and the 50 collars e' and h'' are connected by a sheet-metal sleeve, e', forming an air-passage, through which the dust that may rise in the ash-pit chamber is carried to the fire-chamber above. 55

This dust-flue is a self-cleaning one, and does not become choked up, as do those flues which connect the ash-pit with the smoke-pipe, finally becoming useless unless cleaned 60 out.

Having described my invention, I claim—

The combination of the following elements: the ash-pit a', the plate B, having inclined front b'', the collar e'', dust-flue E, dust-damper e', inclined lower drum-head, h', having the 65 collar h'', drum or combustion-chamber H, fire-pot D, and door P, all arranged and operating substantially as and for the purpose set forth.

JAMES SPEAR.
